United States Patent [19]

Cesarczyk et al.

[11] Patent Number: Des. 309,894

[45] Date of Patent: ** Aug. 14, 1990

[54] COMPUTER PROCESSING SYSTEM

[75] Inventors: Edward J. Cesarczyk, Watertown; Richard R. Dillon, Wellesley; Helmut H. Henneberg, Canton, all of Mass.

[73] Assignee: Bull HN Information Systems Inc., Billerica, Mass.

[**] Term: 14 Years

[21] Appl. No.: 130,338

[22] Filed: Dec. 7, 1987

[52] U.S. Cl. D14/100

[57] CLAIM

The ornamental design for a computer processing system, as shown and described.

DESCRIPTION

FIG. 1 is a top, front, right side perspective view of a computer processing system showing our new design; FIG. 2 is a front elevational view thereof; FIG. 3 is a rear elevational view thereof; FIG. 4 is a right side elevational view thereof on an enlarged scale; FIG. 5 is a left side view thereof on an enlarged scale; FIG. 6 is a top plan view thereof; FIG. 7 is a bottom plan view thereof; FIG. 8 is a top, front right side perspective view of a second embodiment of our design; FIGS. 9 and 10 respectively are right and left side elevational views thereof; and FIG. 11 is a rear elevational view thereof.
